UNITED STATES PATENT OFFICE.

I. N. PHELPS STOKES, OF NEW-YORK, N. Y.

MAGAZINE-GUN.

SPECIFICATION forming part of Letters Patent No. 339,343, dated April 6, 1886.

Application filed December 7, 1885. Serial No. 184,890. (No model.)

To all whom it may concern:

Be it known that I, I. N. PHELPS STOKES, a citizen of the United States, residing at New York, in the county and State of New York, 5 have invented certain new and useful Improvements in Magazine Guns, of which the following is a specification, reference being had to the drawings accompanying and forming a part of the same.

My invention is an improvement in that class of breech-loading fire-arms known as "magazine-guns," and the object of the same is to produce a gun more rapid and certain in its action, stronger in those mechanisms which 15 in arms of this character are commonly of a complicated and delicate character, and containing fewer parts than those heretofore made, and capable of the same action or result.

The general principle of the manipulation 20 or operation of my improved fire-arm is similar in certain respects to that of others now in use—that is to say, the cartridges to a certain number are placed in a cylindrical magazine under and along the barrel. In this they 25 are subjected to spring-pressure, which forces them backward toward the breech, while the operations of loading, ejecting the empty shells, and reloading are effected by the movement of a pivoted lever, which serves as the trigger-guard. My improvements are chiefly in the 30 breech mechanism operated by this lever, and through the instrumentality of which the several operations named are performed.

Heretofore magazine-guns have been devised 35 in which the breech-block was capable of a vertical movement, or one at right angles to the breech, and various devices have been proposed for imparting to such breech-block an intermittent movement by a continuous 40 movement of the operating-lever or trigger-guard. The main advantage of this form of gun is that it dispenses with the usual bolt for forcing the cartridges in the chamber and sustaining the explosion. In addition to this I 45 have secured by devices of novel and improved construction other advantages, which will be set forth in the subsequent description of the features that constitute my invention.

The gun which I have devised, and which 50 contains the improvements which form the subject of this application, is constructed in the following general manner: It has a barrel

of the usual construction, screwed or otherwise secured to a metal case, which contains the breech mechanism and joins the barrel to 55 the stock. Beneath the barrel and entering this case is the magazine and spring therein for delivering the cartridges successively to be inserted in the chamber by the breech mechanism. The hammer and trigger are of 60 the usual pattern, the former being connected to the lever under the trigger, so that it is cocked by the downward movement of the lever. The breech is flush with the forward wall of the breech-case. Against this wall 65 slides the breech-block, which is practically solid. At the rear of the breech-block are stout guides, forming part of the case itself, and which restrict the movement of the block to a path at right angles to the barrel. In one 70 side of the breech-block is a slot of irregular shape, in which enters a pin carried by an arm rigidly connected to the rock-shaft operated by the trigger guard or lever. On the opposite side of the breech-block is an arm 75 pivoted to the side of the breech-case and connected with the aforesaid rock-shaft by a lever that imparts to it an oscillating movement corresponding to the movement of the trigger-guard. This arm extends upward 80 alongside the breech-block, and is then connected with the extractor and injector. These parts are so constructed and combined that a forward and downward movement of the trigger-guard produces a downward movement 85 of the breech-block; but as soon as this has cleared the breech the pin carried by the actuating-arm enters a portion of the slot, in which it ceases for a time to impart any movement to the block. While this is taking place 90 the extractor is operated and thrown backward sufficiently to partially or wholly withdraw a cartridge or shell from the chamber. The breech-block is then encountered again by the pin moving through the slot in its side, 95 and moved farther downward until it passes below the opening of the magazine. Here it takes up a cartridge, and by the reverse movement of the trigger-guard the cartridge is raised to a level with the breech, and then, while the breech-block remains stationary, it is forced into the chamber, which is immediately closed. These, the principal features 100 in the cycle of operation, are attended by cer-

tain others which contribute to the more successful action of the arm, and which are brought about by certain details which will be hereinafter described.

Having thus generally described the nature of the devices composing the breech mechanism and their mode of operation, I will now refer to the drawings for a more specific description of the same.

Figure 1 is a side elevation of the main portion of my improved gun. Fig. 2 is a central vertical section of the barrel, breech-case, and magazine, showing the breech mechanism in its condition immediately following a discharge. Fig. 3 is a view of the gun with the breech-case in section, to exhibit the breech mechanism as it appears at the time when the breech-block has been carried just below the breech or chamber and the extractor is about to be brought into operation. Fig. 4 is a similar view showing the opposite side of the breech mechanism. Fig. 5 exhibits the parts in their relative positions at the time when the extractor has been thrown backward to its fullest extent. Fig. 6 shows the mechanism at the time when the breech-block has reached its limit of downward movement and received a fresh cartridge from the magazine. Fig. 7 is a horizontal section on line $x-x$ of Fig. 6. Fig. 8 shows the gun in condition for firing a second time. Fig. 9 is a detail of the exploding-pin.

The letter A designates the barrel, A' the magazine, B' the stock, and B the breech-case, of the gun. In one or both sides of the latter are openings a , which are closed by close-fitting plates, and which afford access to the interior of the case for purposes of examination or repairs. The barrel is screwed or otherwise firmly united to the breech-case B, and the magazine is similarly secured, both entering the forward end of the case and ending flush with its inner wall. The breech-case is extended in tubular form and secured to the stock in any convenient manner.

C is the hammer, carried by a pin, a' , that passes through the sides of the rear portion of the breech-case. The hammer is actuated by a spring, b' , and sprung by a trigger, e , in the usual manner.

D is the breech-block, which is of hard metal and practically solid. It contains a spring-actuated firing-pin, c' , (shown in Fig. 9.) and in its upper face contains a channel or groove, in which the cartridge lies.

In order that the breech-block may not move too freely or independently by its own weight in the casing, it has attached to it a spring, d , that presses against the side of the casing. The purpose of this will subsequently more fully appear. The breech-block extends from the front to the rear of the chamber formed for it in the breech-case B, and is restricted by these sides to a vertical movement. It does not, however, occupy all of this chamber, spaces being left on each side of it for the arms or levers that control its movement and operate

the extractor. The construction in this particular, however, may be somewhat modified, as recesses for the last-named instrumentalities may be provided in the sides of the case B.

E is the trigger-guard. It is pivoted to the forward and lower part of the breech-case, and, so far as the principle of this invention is concerned, its manner of connection may be greatly varied. In the present case it is carried by a spindle or rock-shaft, E', to which it imparts a partial revolution when it is turned. Its normal position is shown in Figs. 1 and 2, in which it is held against the stock by a spring-catch, e . A curved arm, F, is carried by the axle or spindle of the hammer, and is connected to the lever E by a link, F'. Below the fulcrum of the hammer is a pin, e , that extends into the path of the arm F, so that when the lever E is depressed the arm F is drawn forward and the gun cocked.

In one side of the breech-block D is a slot, f , with double cam-faces. The general direction of the slot is at right angles to the line of movement to the breech-block; but the rear portion is lower or nearer the bottom of the block, and is connected with the higher and forward portion by a nearly vertical part. An arm, G, is rigidly secured to the rock-shaft E', and at its end carries a pin, g , that enters the slot f . The tendency of this arm is to lower the breech-block when the lever E is depressed by the contact of the pin g with the lower cam-face of the slot, and to raise the breech-block when the lever E is raised by the pressure of the pin g upon the upper cam-face of the slot. When the breech-block is in its highest position the pin g is in the forward end of the slot. By depressing the lever E, it is moved backward along the slot and the breech-block is drawn downward. After a certain backward movement of the pin g , however, it enters the vertical portion of the slot f ; but here, as it encounters for a certain part of its path no part of the breech-block, the latter remains stationary. As soon as the pin reaches the lower face of the lower and rear portion of the slot f , however, the breech-block is again set in movement and carried to its lowest position. The converse of this takes place when the lever E is raised. Thus it will be seen that although the movement of the lever E between its limits of movement is continuous, the breech-block which is controlled by it stops for a time in its path. On the opposite side of the breech-block is an arm, H, on a stud, h , secured to the side of the breech-case B. The end of this arm is bifurcated and engages with a pin, h' , set in a block, i , that is carried in a guide, k . To this block i is secured a spring-catch, l , which serves as the extractor and injector. A second arm, H', is pivoted on a stud, h' , set in the side of the breech-case, and the end of this arm, which is bifurcated, engages with a pin, l , set a short distance from the fulcrum of the lever H. The arm H' may be carried by the rock-shaft E'; but with the double purpose of economizing

space and imparting a sudden movement to the extractor, the following means of operating the arm H' by the rock-shaft E' are employed. The arm H' above the fulcrum is cut 5 away, leaving two points, $n\ n'$. The arm is so placed that the rock-shaft E' lies in the cut away portion. Over the arm H' is a hub, o , on the rock-shaft, one half of which is cut away; or two lugs on opposite sides of the 10 shaft would serve the same purpose. A stout spring, o' , secured to the breech-case, bears upon the end of arm H' , just below the point n . Now, when the lever E is depressed and the rock-shaft E' turned the rear edge of the 15 hub o , or the lug which may be used in its stead, encounters the point n' and turns the arm H' downward. This imparts a movement to the lever or arm H , and draws the extractor away from the breech. After a short downward 20 movement the spring o' comes into play and forces the arm H' by a sudden movement through the remainder of its path, and brings the point n up against the forward edge of the hub o . When the lever E is raised again, the 25 arm H' is therefore forced positively upward by the pressure of the hub upon the point n . There is a slight play between the hub and the points $n\ n'$, so that the lever E is moved through a certain space without imparting 30 movement to the arm H' and the extractor. The extractor slides on the guides k up into a recess, p , in the breech. Its position, at the time when a cartridge is received by the 35 breech-block and presented to the breech, is shown in Fig. 7. In its forward movement the spring-catch i' engages with the rim of the shell or draws the cartridge into the breech-chamber. When the cartridge is thus driven home, the spring-catch i' slips over 40 the rim of the shell and into the recess p and alongside of the cartridge. When the lever E is again depressed, the spring-catch, engaging with the opposite side of the cartridge rim, forces the same out of the chamber. 45 In order that the cartridge or the empty shell may be held in engagement with the spring-catch i' , a plate or arm, r , is hinged in a recess, r' , in the breech-case opposite to the catch i' and near the top of the breech block. 50 Combined with this plate is a spring, s , that causes the plate to swing outward into the space above the breech-block when the latter is lowered. When the breech-block is up, it forces this plate into the recess r' ; but as soon as the 55 breech-block is lowered the plate is forced out into the space above it, and its edge forms a guide for the cartridge.

The operation of the gun in detail is as follows: A suitable number of loaded shells are 60 introduced into the magazine by dropping the breech-block and inserting the shells through the breech-case, and the gun brought into condition for firing by raising the lever E . After discharging the piece the lever E is depressed. 65 This draws down the breech-block, as herein-after explained. When the breech-block has passed below the level of the breech-chamber,

or reached the position shown in Fig. 3, it stops for a certain time while the pin g is traveling downward through the vertical part of the slot f . It is during this time that the extractor works, the adjustment of the parts being such that just at the time when the downward movement of the breech-block is suspended, the hub o comes in contact with the point n' and imparts a positive movement to the extractor. The empty shell is thus forced out of the breech-chamber by a positive action, and when free from the breech is ejected by the rapid movement of the arm H , caused by the spring o' , through the opening at the rear of the breech-case. At the moment when this is effected the breech-block is again set in motion and drawn down to its lowest point, the hammer in the mean time being cocked. A fresh shell is 85 then forced out of the magazine on the breech-block, and the lever E raised. The first effect of this is to raise the breech-block to bring the cartridge carried by it into line with the breech-chamber. At this point it rests while the pin g is moving up through the vertical portion of the slot f ; but while this is taking place the hub o engages with the point n , and the arm H is driven positively forward. By 90 this means, and while the breech-block is stationary, the shell is forced home in the breech-chamber. The breech-block then starts upward, closes the breech, and the lever E is locked. The piece is then in condition for a 95 second discharge.

Of the details of mechanism here shown which are common to other guns I have given no specific description, as their functions and mode of operation are well understood. I would state, however, that I use a movable 100 cover, T , on the breech-case, or an equivalent device which is readily removed to facilitate access to the breech-mechanism.

The specific construction of the lever H' , or the manner of its connection and operation by 110 the hub o on the rock-shaft, I do not claim, except as it may enter into the combinations which I have herein set forth.

I do not limit myself to the exact construction of the parts herein described. Particularly is this the case with those devices or parts which are not new in themselves. For example, the action may be considerably varied; or, in other words, the lever E , in lieu of forming a trigger-guard and being placed 120 below the breech-case, may lie alongside the same, and so for many other obvious modifications.

What I claim is—

1. In a magazine-gun, the combination, with 125 a breech-block capable of a movement at right angles to the barrel, and adapted to close the breech when in its highest or firing position, of a lever pivoted to the breech-case in position to be turned or operated by hand, an 130 arm operated by said lever and engaging with a slot in the side of the breech-block, the said slot being formed substantially at right angles to the path of movement of the breech-block

with a central vertical portion, so as to permit the engaging arm to move through it during a certain portion of its path of movement without imparting movement to the breech-block, whereby, by a continuous movement of the lever up or down, an intermittent movement is imparted to the breech-block, as and for the purpose specified.

2. In a magazine-gun, the combination, with 10 a breech-block capable of a movement at right angles to the barrel and adapted to close the breech when in its highest or firing position, of a hand-lever pivoted to the breech-case, an extractor and injector connected with and operated by said lever, and an arm operated by 15 said lever and engaging with a slot in the breech-block, said slot being formed substantially at right angles to the path of movement of the breech-block with a central vertical 20 portion, so as to permit the engaging arm to move through it during a certain portion of its path of movement without imparting movement to the breech-block, whereby, by a continuous movement of the lever up or down, an 25 intermittent movement is imparted to the breech-block, as and for the purpose specified.

3. The combination, in a magazine-gun, of 30 a vertically-movable breech-block adapted, when in its highest position, to close the breech, a reciprocating extractor and injector, and a pivoted arm or lever connected therewith, a hand-lever connected with and operating the extractor-lever, and an arm or lever turned or operated by the hand-lever and engaging 35 with a slot in the side of the breech-block, said slot being so formed as to cause the breech-block by a continuous movement of the hand-lever to be moved intermittently up or down in the breech-case, as herein described.

4. The combination, in a magazine-gun, of 40 a vertically-movable breech-block adapted, when in its highest position, to close the breech, a reciprocating extractor and injector, the path of movement of which is parallel to the axis of the barrel, and a pivoted arm or lever connected therewith, a hand-lever connected with and operating the extractor-lever and an arm or lever turned or operated by the hand-lever and engaging with a 45 slot in the side of the breech-block, said slot being so formed as to permit the breech-block to remain stationary for a certain time during the movement of the arm or lever and while the extractor or injector is operating, as herein 50 set forth.

5. The combination, in a magazine-gun, with 55 a vertically-movable breech-block adapted, when in its highest position, to close the breech, and provided with a slot in its side, of 60 an arm or lever pivoted within the breech-case and engaging with the slot, which is so formed as to cause an intermittent movement to be imparted to the breech-block by a continuous movement of the lever, a second lever placed on the opposite side of the breech-block, an extracting and injecting device operated thereby, and a hand-lever without the

breech-case connecting with and operating the two levers, these parts being constructed and arranged for operation in substantially 70 the manner set forth.

6. The combination, in a magazine-gun, with 75 a breech-block adapted to be moved vertically in the breech-case and in its highest position to close the breech, of an arm or lever engaging with a slot in the side of the breech-block, a guide supported in the breech-case, an extractor and injector arranged to slide therein, an arm or lever for operating the said extractor and injector, and a hand-lever operatively connected with the two arms or levers, all as set forth.

7. A breech mechanism for magazine-guns, consisting of the following devices combined for operation in the manner set forth, to wit: 80 a vertically-movable breech-block adapted in its highest position to close the breech, and having a slot, substantially as described, in one of its sides, an extractor and injector arranged to slide in a guide placed beside the breech-block and in line with the bore or chamber, a rock-shaft in the lower forward part of the breech-case, a lever or arm connected therewith and engaging with the slot in the breech-block, a system of levers operated by the rock-shaft and connecting with the extractor and injector, and a hand-lever without the breech-case for imparting movement to the rock-shaft, 85 all as set forth.

8. A breech mechanism for magazine-guns, 90 consisting of the following instrumentalities combined for operation in the manner set forth, to wit: a breech-block arranged to move vertically in the breech-case and having a slot 95 in one of its sides, an extractor and injector arranged to slide in a guide placed beside the breech-block and in line with the bore or chamber, a rock-shaft in the lower forward part of the breech-case, an arm or lever rigidly connected therewith and engaging with the slot 100 in the breech-block, a lever connected with the extractor and pivoted in the lower part of the breech-case, an arm or lever operated by the rock-shaft and connected with the extractor-lever, whereby a movement of the rock-shaft is caused to move the extractor and injector in its guide, and a lever without the 105 breech-case for imparting movement to the rock shaft, as described.

9. In a magazine gun, the combination, with 110 the vertically-movable breech-block and mechanism for operating the same, consisting of a hand-lever and rock-shaft operating an arm that engages with a slot in the side of the breech-block, of an extractor and injector arranged 115 to move in a guide on one side of the breech-block and in line with the barrel, a bifurcated lever pivoted below the guide and engaging with the extractor, and a bifurcated connecting arm or lever operated by the rock-shaft 120 and hand-lever and engaging with the extractor-lever, as and for the purpose set forth.

10. The combination, with the breech-block arranged to move vertically within the breech-

case and to close, when in its highest position, the breech, of a rock-shaft below and in front of the breech-block, an arm or lever carried by said rock shaft and entering or engaging with a slot in the side of the breech-block, which slot has such shape that for a certain time during the movement of the lever or arm the latter moves in the slot without imparting movement to the breech-block, and extracting to and injecting devices adapted to be operated or brought into operation by the rock-shaft during the time when the breech-block is at rest, as and for the purpose described.

11. The combination, with a breech-case, of a vertically-movable breech-block, an extractor and injector placed to one side of the breech-block, means for imparting an intermittent movement to the breech-block and for operating the extractor and injector while the breech-block is stationary, a firing-pin passing through the breech-block, and a hammer pivoted in the rear of the breech-case, all as set forth.

12. In a magazine-gun, the combination, with a breech-block and mechanism for imparting a vertical movement thereto, of an extractor 25 and injector moving in line with the barrel or chamber, and a breech-case inclosing the parts named and having an opening in its rear and above the hammer to permit the ejection of the shells withdrawn by the extractor, as set forth.

13. In a magazine-gun, the combination, with a vertically-movable breech-block and the operating mechanism associated therewith, of a breech-case containing the said mechanism, 35 and provided with an opening in its rear and above the hammer for permitting the insertion and ejection of the shells, and provided with a movable cover or lid, as herein set forth.

I. N. PHELPS STOKES.
